(57) **CLAIM**

The ornamental design for a flight simulator cockpit as shown and described herein.

DESCRIPTION

FIG. 1 is a top, front, right side perspective view of a flight simulator cockpit according to the present disclosure;

FIG. 2 is a top, rear, right side perspective view of the flight simulator cockpit shown in FIG. 1;

FIG. 3 is a front view of the flight simulator cockpit shown in FIG. 1;

FIG. 4 is a rear view of the flight simulator cockpit shown in FIG. 1;

FIG. 5 is a left side view of the flight simulator cockpit shown in FIG. 1;

FIG. 6 is a right side view of the flight simulator cockpit shown in FIG. 1;

FIG. 7 is a top view of the flight simulator cockpit shown in FIG. 1; and,

FIG. 8 is a bottom view of the flight simulator cockpit shown in FIG. 1.

The broken lines in the drawings are for the purpose of depicting unclaimed portions and/or environmental matter and form no part of the claim.

1 Claim, 8 Drawing Sheets
